UNITED STATES PATENT OFFICE.

WILLIAM J. RANDOLPH, SR., AND WILLIAM J. RANDOLPH, JR., OF MOSCOW, NEW YORK.

RAIL-BOND.

979,202.

specification of Letters Patent. Patented Dec. 20, 1910.

Application filed July 1, 1910. Serial No. 569,926.

To all whom it may concern:

Be it known that we, WILLIAM J. RANDOLPH, Sr., and WILLIAM J. RANDOLPH, Jr., citizens of the United States, residing at 5 Moscow, in the county of Livingston and State of New York, have invented a new and useful Improvement in Rail-Bonds, of which the following is a specification.

This invention relates to improvements in 10 rail bonds or connections which serve to connect electrically the adjacent ends of the rails of a railway track through the fish plates for the purpose of adapting the track to be used as a conductor of electric current. 15 The object of the invention is to provide a rail bond of simple and inexpensive construction which will form a secure and positive electrical connection between the rails and the fish plates and which is so constructed 20 that it can be easily and quickly secured in position for connecting the rails and fish plates which are commonly used in track construction and requires no separate securing device for this purpose, nor any change 25 nor alteration in the construction of the rails and fish plates.

In the accompanying drawings: Figure 1 is a side elevation of a portion of a railroad track showing a rail joint provided with 30 rail bonds embodying the invention. Fig. 2 is a sectional plan thereof on line 2—2, Fig. 1. Fig. 3 is a transverse sectional elevation thereof on line 3—3, Fig. 1, on an enlarged scale. Fig. 4 is a fragmentary sectional elevation of one end of the rail bond. Fig. 5 is a perspective view of the rail bond.

Like reference characters refer to like parts in the several figures.

The rails and fish plates to which the rail bonds are adapted to be secured may be of 40 any usual and suitable construction. In the construction shown, A A represent the abutting rails and B B the fish plates which connect the ends of the rails on both sides 45 thereof. These fish plates are secured to the rails by means of the usual bolts C which pass through holes in the plates and in the web portions of the rails.

D D represent the rail bonds which connect the opposite ends of the fish plates to the rails and are preferably arranged on both sides of the rail. Each rail bond consists of a plate or body portion d which extends lengthwise of the rail and has offset 55 end portions or flanges d' d'', the ends of which are adapted to engage the web por-

tion of the rail and the end portion of the fish plate to form an electrical connection between these two members. The end flange d' of the rail bond which engages with the 60 rail is preferably made somewhat longer than the end flange d'' which engages with the fish plate, so that the body portion d of the rail bond will extend substantially parallel to the rail when the rail bond is in 65 position thereon. Intermediate between its ends, the body portion of the rail bond is provided with a suitable hole d³ through which a bolt d⁴ or other suitable securing device is adapted to pass. The bolt d⁴ extends through the usual holes which are provided in the rail and end portion of the fish plate for receiving the connecting bolts C. The rail bonds on the opposite sides of the 70 rail at the ends of the fish plates are preferably directly opposite to each other so that the bolt d⁴ serves to secure the corresponding rail bonds in position.

The end portions or flanges d' d'' are provided with suitable prongs or contact points which are adapted to be forced into the material of the rail and fish plate when the rail bond is secured thereto and which insure a good contact therewith. In the construction 80 shown, the prongs consist of pins or studs E which have threaded stems e which are screwed into suitable holes in the end flanges d' d'' of the rail bond. Each of these studs is provided at its outer end with a central contact point or prong e' and an annular 85 edge portion or contact ring e² which surrounds the contact point e' and is spaced therefrom.

In securing the rail bond to the rail and fish plate, the body portion of the rail bond is hammered, or otherwise driven, sufficiently to bring the contact points and the annular edges of the studs E into positive engagement with the rail and fish plate, the contact points and edges preferably penetrating a short distance into the material of the rail and fish plate so as to form an intimate electrical contact therewith. The space 90 between the annular edge e² and the contact point e' is preferably filled with a suitable cement or packing e³ which serves to prevent moisture from gaining access to the contact point and interfering with the electrical connection through the same. The employment 95 of separate detachable studs permits the studs or contact points of the rail bond to be made of a harder grade of steel than the 100 105 110

body portion of the bond, and also permits the studs, when worn or broken, to be readily removed and new studs inserted. While the construction described is preferable, any 5 other suitable detachable contacts may be employed, or, if desired, the rail bonds may be provided with contact points integrally formed therewith.

The rail bonds can be easily and quickly 10 secured in place at the opposite ends of the fish plates. It is only necessary to place the rail bonds in position opposite to each other on opposite sides of the rail and with their holes d^3 in alinement with the bolt holes in 15 the corresponding ends of the fish plates and rail so that the bolts d^4 can be readily inserted through these holes for securing the rail bonds in position. The body portions 20 of the rail bonds are then tapped with a hammer or sufficient force is applied thereto in some other suitable manner to bring their contact points into intimate engagement with the rail and fish plates, in which position they can be retained by tightening the 25 nuts on the bolts d^4 . The bolts d^4 also assist in securing the fish plates to the rail and thus take the place of the bolts which are ordinarily employed for this purpose. The construction of the rail joint is thus not 30 weakened by applying the rail bonds thereto.

In the construction shown, rail bonds are employed at opposite sides of the rail at both ends of the fish plates. The rail bonds 35 on one side may be dispensed with if desired and the electric connection completed through only one of the fish plates instead of through both. The rail bonds, when in position, lie close to the rail where there is 40 little danger of their becoming displaced or broken by depending parts of a train passing over the track or in any other manner. They can be cheaply manufactured and quickly attached to the rail and do not require 45 any additional hole or other alteration to be made in the fish plate and the rail for securing the rail bond thereto.

We claim as our invention:

1. The combination with a rail and fish 50 plate, of a rail bond for electrically connecting said rail to said fish plate comprising a connecting body portion extending substantially parallel with said rail and spaced therefrom, said body portion being provided at its ends with contact portions which are adapted to engage the sides of said rail and said fish plate, and means engaging said body portion between said contact portions for securing said rail bond to said rail and 55 said fish plate, substantially as set forth.

2. The combination with a rail and fish

plate, of a rail bond for electrically connecting said rail and said fish plate, having offset contact portions at its opposite ends which are adapted to engage the sides of 65 said rail and said fish plate, and means common to said rail and said fish plate for securing said rail bond in position on said rail and clamping said fish plate between said rail bond and said rail, substantially as 70 set forth.

3. The combination with a rail and fish plate, of a rail bond for electrically connecting said rail and said fish plate comprising a connecting body portion extending substantially parallel with said rail and provided at its opposite ends with contact portions which project inwardly therefrom and are adapted to engage the sides of said rail and said fish plate, and means for securing 80 said rail bond to said rail and said fish plate, substantially as set forth.

4. The combination with a rail and fish plate, of a rail bond for electrically connecting said rail and said fish plate, comprising 85 a connecting body portion extending substantially parallel with said rail and provided at its ends with offset contact portions which are adapted to engage the sides of said rail and fish plates, and a bolt extending through said rail and fish plate for securing said rail bond in position thereon, substantially as set forth.

5. The combination with a rail and fish plate, of a rail bond for electrically connecting said rail and said fish plate, comprising a connecting body portion having offset end portions provided with detachable contact points which are adapted to engage said rail and said fish plate, and means for securing 100 said rail bond to said rail and fish plate, substantially as set forth.

6. The combination with a rail and fish plate, of a rail bond for electrically connecting said rail and said fish plate, comprising 105 a connecting body portion having offset end portions provided with contact points and contact rings surrounding the same and spaced therefrom, said points and rings being adapted to engage the sides of said rail and fish plate, a packing between said points and said rings, and means for securing said rail bond in position on said rail and said fish plate, substantially as set forth.

Witness our hands, this 30th day of June, 110 1910.
